UNITED STATES PATENT OFFICE

172,023

COMBINATION COIN AND KEY HOLDER

William Thomas Henry, Socorro, N. Mex.

Application September 25, 1953, Serial No. 26,956

Term of patent 14 years

(Cl. D17—14)

To all whom it may concern:

Be it known that I, William Thomas Henry, a citizen of the United States of America, residing at Socorro, in the county of Socorro and State of New Mexico, have invented a new, original, and ornamental Design for a Combination Coin and Key Holder, of which the following is a specification, reference being had to the accompanying drawing, forming part thereof.

Figure 1 is an elevational view of a combination coin and key holder, embodying my new design.

Figure 2 is a view of the coin slot.

Figure 3 is a view of the key holder end of a combination coin and key holder, embodying my new design.

Figure 4 is a side elevational view thereof, and

Figure 5 is an enlarged fragmentary sectional view, on lines 5—5 of Figure 1, showing the coin retaining lip internally of the coin slot.

The broken lines appearing in Figure 1 are for illustrative purposes only.

I claim:

The ornamental design for a combination coin and key holder, substantially as shown and described.
